GARMENT HANGER

Filed May 24, 1932

UNITED STATES PATENT OFFICE

LOUIS M. MARBLE, OF CANTON, PENNSYLVANIA

GARMENT HANGER

Application filed May 24, 1932. Serial No. 613,280.

This invention relates to garment hangers; and it comprises a garment hanger provided with a head, advantageously having curved front and rear faces, and having a flat bottom surface, and a pair of shoulder bars each provided at its upper extremity with a flat end complementary to substantially half of the bottom surface of the head, and being firmly united thereto by glue, nails or the like, whereby the shoulder bars meet in the substantial center of the head and are inclined downwardly with respect thereto; and it further comprises a head for garment hangers so shaped that when joined to the shoulder bars described such bars are forwardly as well as downwardly inclined with respect to the center of the head; all as more fully hereinafter set forth and as claimed.

In the present invention a hanger is provided in which the shoulder bars incline forwardly and downwardly in their relation to the center of the hanger in order that garments hung on the hanger shall hang without wrinkling. The rear surface of the central portion of the hanger against which the garment rests is sloped or inclined in order to permit the neck or collar of the garment to hang in its natural position without breaking back or wrinkling.

This construction results in a hanger which permits of ease in assembly and economy of manufacture as well as the highly advantageous features above mentioned.

In the prior art attempts have been made to provide a hanger having forwardly inclining shoulder bars by making the hanger in two pieces and joining them at the center with some form of joint which permits the angled construction desired, but this construction either requires a very complicated and hence undesirable joint or leaves the hanger structurally weak and hence not durable. Hangers have also been made which are constructed of metal, the shoulder bars being separately constructed and joined to a head adapted to give the correct inclination to the shoulder bars, but such hangers have been found undesirable because of their high cost of construction and inflexibility of design.

According to my invention the hanger is made in three pieces, namely; a center or head and two shoulder bars, the head being machined to form a forward angle and the shoulder bars being connected to the head on its bottom surface in such a manner that they are given a forward as well as downward inclination. This construction affords an entirely new method of producing angled relationship between the shoulder bars and the center of the hanger in which the joints are simple as well as strong and durable.

Several embodiments of my invention are shown in the accompanying drawing where-

Fig. 1 is a perspective view of a preferred form of hanger having two bent arms joined to an angled head;

Fig. 2 is a plan view of the same;

Fig. 3 is a central vertical section taken through the line 3—3 of Fig. 2;

Fig. 4 is a plan view of a slightly modified form of hanger in which the shoulder bars are straight and the angle in the head is less extreme than before, the shoulder bars however being attached to the head in a manner similar to that shown in Fig. 1;

Fig. 5 is a further modification showing a hanger having straight shoulder bars and a very slight angle in the head;

Fig. 6 is a detailed sectional view showing the method of fastening the shoulder bars to the under-surface of the head; and

Fig. 7 is a perspective view of a head machined to form an angled joint surface for the shoulder bars showing its contour and flat bottom surface.

In the drawing in which like reference numerals designate corresponding parts throughout the several views, element 1 is a wooden head or center comprising the central portion of a hanger. The head 1 has a rounded top surface and front and rear surfaces which are advantageously machined to provide an obtuse forward angle resulting in the back of the head 1 being rounded or convex and the front being slightly concave. The head has a smooth bottom surface 2 to which is attached a pair of shoulder bars 3 and 4 each provided at its upper extremity

with an angled cut surface (5 and 6), which join the bottom surface of the head so as to meet in its center. The cut surfaces of the shoulder bars are glued to the bottom surface 5 of the head and are further secured by means of small nails 7, as shown in Fig. 6, the shoulder bars being so proportioned as to carry out the contour of the top and sides of the head without interruption when attached 10 thereto. A round horizontal cross-bar 8 serving as a hanger for trousers or like apparel is fitted at each end into suitable recesses in the shoulder bars and is held in place by means of small nails 9. A wire 15 hanging hook 10 terminating at its bottom extremity in a head 11 extends vertically through the central portion of the head, as shown in Fig. 6. In the preferred form of hanger shown in Figs. 1, 2 and 3 the head is 20 machined to give an extreme forward angle and the shoulder bars are also considerably bent. When attached to the head the shoulder bars are given an extreme forward angle with respect to the center of the head due to 25 the angle in the head and bars. The forward inclination of the shoulder bars with respect to the center of the head has the result that when garments are hung on the hanger and the hanger hung up by the hook the weight 30 of the garment makes the hanger tilt forward to a marked extent, supporting the garment in its most natural position at the collar and the back, and preventing to the maximum degree the breaking back or wrinkling of 35 the garment on the hanger. The position which the hanger assumes when thus weighted by a garment is shown in Fig. 3. The head of the hanger may be sloped on its rear face to assist in the hanging of the garment 40 on the hanger, without affecting the smooth joints between the shoulder bars and the head, as further shown in Fig. 3.

In the modification shown in Fig. 4 the use of straight shoulder bars and the lesser angle 45 in the head brings about the result that when the hanger is hung by the hook the head inclines forwardly but to a less extent than in the form shown in Fig. 3.

In Fig. 5 the head of the hanger has a very 50 slight forward angle which results in a correspondingly smaller forward inclination of the head when hung from the hook.

By the arrangement of the parts described; I have provided means by which any one of 55 a number of known designs of garment hanger may be inexpensively constructed by merely varying the angle in the head to the degree desired while maintaining the essential features of strength and simplicity of construc- 60 tion.

The arms of a hanger made in accordance with my invention may be either straight or bent as desired.

What I claim is:

65 1. A garment hanger comprising a head

having a flat bottom surface, hanging means carried by said head and two shoulder bars each provided at its upper extremity with an angled flat surface complementary to a portion of said flat bottom surface of the head 70 and securely attached thereto whereby the shoulder bars are given a downward inclination with respect to the head.

2. A garment hanger comprising a curved head provided with a concave front face, a 75 convex rear face, and a flat curved bottom surface, two shoulder bars each provided at its upper extremity with an angled flat surface complementary to a portion of said flat bottom surface of the head and securely attached 80 thereto, whereby the shoulder bars are given a forward as well as downward inclination with respect to the head, and hanging means carried by said head.

3. A garment hanger according to claim 2, 85 in which the convex rear face of the head is forwardly inclined to assist in the prevention of wrinkling at the collar of garments hung thereon.

4. A garment hanger according to claim 2, 90 in which the shoulder bars are each forwardly curved to assist in the prevention of wrinkling of garments hung thereon.

In testimony whereof, I have hereunto affixed my signature.

LOUIS M. MARBLE.
